REFRIGERATING APPARATUS

Jesse G. King, Dayton, Ohio, assignor, by means assignments, to General Motors Corporation, a corporation of Delaware

Application September 30, 1930, Serial No. 485,366
Renewed October 5, 1935

5 Claims. (Cl. 62—4)

This invention relates to refrigerating apparatus and more particularly to a control mechanism therefor.

It is one of the objects of the invention to provide in a refrigerating system of the type in which a control mechanism is mounted upon a resilient base or support, an improved auxiliary means which may be operated from a convenient point to give a considerable range of modification of the temperature limits normally supplied by the control mechanism.

It is a further object of the invention to provide improved operating means mounted on the outside of a refrigerator cabinet in a convenient location together with improved means for connecting the operating means and control mechanism of the refrigerator for modifying the operation of the control means to provide different refrigerating temperatures according to the users' needs.

Another object of the invention is to provide operating means on the exterior of a refrigerator cabinet which is connected to the control mechanism of a refrigerator for providing a defrosting cycle.

Further objects and advantages of the present invention will be apparent from the following description, reference being had to the accompanying drawings, wherein a preferred form of the present invention is clearly shown.

In the drawings:

Fig. 1 is a front view of a refrigerator cabinet having a portion broken away disclosing one embodiment of the present invention;

Fig. 2 is a fragmentary view of the operating handle and dial of my invention;

Fig. 3 is an enlarged view of my control mechanism shown in Fig. 1;

Fig. 4 is a section shown on line 4—4 of Fig. 3, and

Fig. 5 is a section through the operating mechanism shown in Fig. 2.

Referring to the drawings and more particularly to Fig. 1, there is shown a refrigerator cabinet 20 having a food storage compartment 21 in its upper portion and a compressor or machinery compartment 22 in its lower portion. Within the machinery compartment 22, a horizontal base 23 is resiliently supported on either side by coil springs 24 which rest upon brackets 25 fastened to the framework of the cabinet. Upon this resiliently supported base 23 is mounted a compressor 26 which is driven by a motor 27 and a belt 28. The compressor 26 withdraws refrigerant from the evaporator 100 located in the food

storage compartment 21 of the refrigerator cabinet through a conduit 29 and forces it through the condenser 30 into the receiver 31. The liquid refrigerant is conducted from the receiver to the evaporator 100 through the conduit 32.

The compressor is operated intermittently according to predetermined high and low pressures, consequently high and low temperatures of the evaporator 100 through the control of the motor 27 by the control or switch mechanism 33 which is also mounted upon the resiliently supported base 23. The control mechanism 33 is more particularly shown in Fig. 3 and comprises a pressure operated device or switch mechanism which makes and breaks the circuit of the electric motor 27 which drives the compressor 26. The operation of the pressure control switch is modified by a resilient adjusting means and is also provided with an auxiliary adjusting means independent of the first means and adapted to be positioned manually and whose function is to modify the action of the first means.

The pressure responsive control mechanism 33 consists of a hollow metallic bellows 38 which is sealed at the top and which is connected at the bottom by means of conduit 41 to the circuit of the refrigerator system. An operating member or lever 42 pivoted on the ears 43 of the elevated platform 40 follows the movement of the bellows 38 by being pivoted thereto by a pin 44. The double lever 47 straddles the lever 42 and is pivoted thereto by a pin 52. One end of the lever 47 is connected to one of the switch contacts 45 by a link 48 cooperating switch contact 56 mounted on the base 39 of the control mechanism. A snap action of the contact 45 with respect to the contact 46 is provided by means of a cam system which includes the hardened steel nose 49 fastened to the outer end of the lever 47 against which a hardened steel roller 50 is biased by a carrier 51 and a spring 52a.

After the pressure builds up within the flexible metallic bellows 38 the latter expands and since the lever 42 is pivoted to this bellows by the pin 44 and fulcrumed to the supporting frame 45 of the device as at 43, it is evident that the bellows will raise the operating lever 42. The upward movement of the lever 42 is resisted by a yieldable adjustable system comprising a coil spring carried within an adjustable casing 52 and bearing against a plunger 53 which acts against the extremity 54 of the lever 42. When the pressure decreases and the bellows 38 collapses, downward movement of the lever will be resisted by a coil spring 54 whose tension may be 55

regulated by nuts 55 carried on a vertical threaded rod 56 pivoted to lever 42. A balancing spring 57 adjusted by nuts 58 is used on the opposite side of the base 39 of the device for resisting the tension of the spring 54. The springs 54 and 57 as well as the resilient adjusting system comprising the plunger 53 and an adjustable cap 62 are provided for preferably so adjusting what might be termed normal preadjustment, that is, for maintaining the pressure corresponding to a particular temperature which is ordinarily suitable for every day operation of the refrigerator in which the system is used. The extremity 63 of the lever 42 bears against the plunger 53 only on the upward action of the lever 42. After lever 42 begins to descend, the extremity 63 does not touch the plunger 53, thus the plunger 53 affects the starting pressure but not the stopping pressure. The cap 62 is therefore a starting adjustment. The temperature provided by the mechanism thus described is sufficient to cool foodstuffs stored in the usual compartments of the cabinet cooled by the cooling unit or evaporator 100.

25 The apparatus is usually adjusted at the factory or in the field by the service man for such normal operation but suitably tensioning the springs 54 and 57 as well as the resilient adjusting system 62 and 53 and in such condition the lever 42 will have its upward and downward movements resisted so that it will open and close the circuit of the driving motor 24 only at the maximum and minimum pressure temperature points for which the tension corresponds. It is evident that by interposing a resistance to the downward descent of the lever 42 the operation of the switch contacts will be delayed so that the system will continue operating for a longer period of time, thus prolonging the cooling cycle of the system. Likewise after the resistance to the downward descent of the lever 42 is increased, it will require a greater effort on the part of the diaphragm 38 to pull the lever down into contact breaking position (the descent of the lever 42 causing the raising of contact 45 away from the contact 46, thus breaking the circuit).

For the purpose of providing a plurality of ranges of temperature at will, means are provided for interposing such a resistance. To this end an L shaped bracket 70 is fastened to the base 39 of the control mechanism to which is fastened one end of a rotatable shaft 71. Upon the projecting end of this rotatable shaft is mounted a sprocket 72 spaced from the L shaped bracket 70 by a long collar 73. The shaft 71 has its projecting end slotted and carried a coil spring 74 thereon which has one end hooked into the slot in the shaft 71 and which has its other end projecting so as to engage the protruding end of the pin 52 which is carried by the lever 42. The pin 52 is engaged by the spring in such a manner that when the lever 42 descends the pin 52 engaging the protruding end of the coil spring 74 will have its downward descent resisted to an extent corresponding to the degree to which the spring 74 is wound. The spring 74 carried by the shaft 71 may be wound by the rotation of sprocket 72 so that a correspondingly greater tension is caused to bear against the pin 52 and therefore against the downward descent of the lever 42.

After the refrigerator has been in operation for an appreciable period, a considerable amount of frost will collect around the coils of the evaporator 100 and act substantially as an insulator.

In order to defrost the refrigerating element or evaporator it is necessary to shut down the operation or to discontinue the operation of the compressor and this is effected by completely blocking the movement of the control mechanism by interposing an obstruction to the downward movement of the lever 42. For this purpose a blocking arm 76 is attached to the sprocket wheel 72 as shown in Fig. 4. The sprocket wheel may be turned clockwise to cause the blocking arm 76 to strike the projecting pin 98 and separate the contacts 45 and 46 to stop the compressor.

According to the present invention, means are provided for turning the sprocket wheel 72, 15 the shaft 71, and consequently the coil spring 74 and the blocking arm 76 from a convenient but remote point on the refrigerator cabinet. To this end, a perforated plate 80 is fastened upon the upper portion of the front side of the refrigerator cabinet at one side of the door. A small bearing member 81 is riveted to this plate and carries a short shaft 82 which is rotatably mounted therein and which has an end projecting through the plate 80. This shaft 82 carries an operating 25 handle 83 upon its projecting end. A recess 84 is formed in the post at the corner of the cabinet behind the lower portion of the plate 80 and the rear portion of the shaft 82 as well as the bushing 81 are positioned in this recess. A sprocket 30 wheel 85, similar to the sprocket 72, is mounted upon the rear end of the shaft 82. For the purpose of holding the sprocket 85 in any of a plurality of positions, a plurality of apertures 86 are provided in the plate 80 arranged in a circle 35 about the shaft 82. A stud 87 carries a spring pressed ball 88 which projects into one of the apertures 86 and holds the shaft 82 in the desired position. An ornamental dial 89 is provided on the exterior of the refrigerator cabinet 20 for 40 cooperating with the operating handle 83 to indicate the various ranges of temperature as well as the defrosting position.

The sprocket chain 90 passes from the sprocket 85 and has a wire or cable connected to 45 either end, these wires or cables being designated 91 and 92. These wires 91 and 92 extend through a pair of conduits 93 and 94 which pass downwardly through a passage in the corner post of the refrigerator cabinet 20 and which have their 50 ends clamped to a post 95 which is mounted upon the base 39 of the control mechanism 33. The lower end of the wires 91 and 92 are fastened to the ends of a second sprocket chain 96 which passes around the sprocket 72 to operate the coil spring 74 and the blocking arm 76 to interpose a resistance to the downward descent of the lever 42 or to break the switch contacts of the control mechanism.

By turning the operating handle 83 to the 60 various positions marked 2, 3, 4, 5 and 6 upon the dial 89 shown in Fig. 2, various ranges of temperature may be provided since the sprocket chain 90, the wires 91 and 92, and the sprocket chain 96 are moved to tension the spring 74 65 which in these positions bear against the pin 52 which is mounted upon the lever 42 of the control mechanism. For defrosting, the operating handle is turned to the position designated by the reference character 97 which moves the 70 blocking arm 76 into contact with the pin 98 to separate the switch contacts 45 and 46 of the control mechanism.

Thus it will be seen that I have provided a 75 convenient and attractive means whereby the

resiliently mounted control mechanism of a refrigerating apparatus may be operated from a remote point to provide various ranges of temperature and to provide a defrosting means.

5. While the form of embodiment of the invention as herein disclosed constitutes a preferred form, it is to be understood that other forms might be adopted, all coming within the scope of the claims which follow.

10. What is claimed is as follows:

1. Refrigerating apparatus including a refrigerator cabinet, a base resiliently supported by the cabinet, refrigerant supply means supported upon the base, control means for the refrigerant supply means also supported upon the base, and means for modifying the operation of the control means including a rotatable operating handle mounted on a wall of the cabinet, a casing fastened to the control means and extending 20 to a point adjacent said operating handle and a wire enclosed in the casing for connecting the operating handle to the control means.

2. Refrigerating apparatus including a refrigerator cabinet, a base resiliently supported by the cabinet, refrigerant supply means supported upon the base, control means for the refrigerant supply means also supported upon the base, and means for modifying the operation of the control means including an operating handle mounted on a portion of the cabinet, means for engaging the control mechanism and mounted on the control mechanism, and means connecting said last mentioned means and the operating handle including a plurality of sprockets, and a sprocket 35 chain.

3. Refrigerating apparatus including a control mechanism, a shaft having means thereon for modifying the operation of the control mechanism, a second shaft having an operating handle 40 thereon, positioned remote from said first shaft, a gear connected to each shaft and a chain for rotatively connecting the gears.

4. Refrigerating apparatus including a cabinet having a door and a door jamb therefor having a passage therein extending vertically along 45

one side of the door opening, a refrigerating system including an evaporating means for cooling the interior of the cabinet, a control mechanism having means for controlling the refrigerating system for maintaining the evaporating means at 5 a normal average temperature, said control mechanism also having means for controlling the system for obtaining temperatures other than normal of the evaporating means, said control mechanism being positioned within the outer 10 walls of the cabinet, a movable means having an operating handle positioned on the exterior of the cabinet, means for indicating the normal setting of the operating handle and a setting other than normal, and means extending through the 15 passage in the door jamb for connecting the movable means and the control mechanism for obtaining the normal average temperature and a temperature other than normal of the evaporating means. 20

5. Refrigerating apparatus including a cabinet having spaced inner and outer walls, insulating means therebetween, and a vertically extending passage formed between said walls and extending through the door jamb, a refrigerating system including an evaporating means for cooling the interior of the cabinet, a control mechanism having means for controlling the refrigerating system for maintaining the evaporating means at a normal average temperature, 25 said control mechanism also having means for controlling the system for obtaining temperatures other than normal of the evaporating means, said control mechanism being positioned within the outer walls of the cabinet, a movable 30 means having an operating handle positioned on the exterior of the cabinet, means for indicating the normal setting of the operating handle and a setting other than normal, and means extending through the passage for connecting the movable means and the control mechanism for obtaining the normal average temperature and a temperature other than normal of the evaporating means. 35

JESSE G. KING. 45
